(57) **CLAIM**

The ornamental design for a controller for digital video disk player, as shown and described.

DESCRIPTION

FIG. 1 is a perspective view of a controller for digital video disk player;

FIG. 2 is an enlarged front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

In the drawings, the broken lines in FIGS. 1 and 2 show portions of interior elements and buttons that form no part of the claimed design.
